Henry L. Shepherd of Dayton, Montgomery County, Ohio,
Letters Patent No. 2158, dated January 8, 1850.

The Schedule referred to in these Letters Patent and making part of the same:

To all whom it may concern:

Be it Known
that I, Henry L. Shepherd, of Dayton, Montgomery Co.
Ohio, have invented or produced a new combination of ornamental designs and configuration for a Cooking Stove represented in the annexed drawings, making a part of this specification, in which fig. 1 exhibits a side plate, fig. 2 the front plate below the hearth and fig. 3 one half of the front plate above the hearth, the other half being counterpart.

The two side plates and their contained doors exactly match each other, only one therefore (a fig. 1) is shown. Both side and front plates are bordered with a moulding such as is represented at (b fig. 1). The doors in the side plates are all decorated with moulding such as that shown (c & m) on the oven door (d). (c) being a half round bead around the outer edge, and (m) a scolloped beading following the outline of the door, somewhat within the other (e) is the lower oven door. (f) is one of the end fire doors. (g fig. 3) is one of the pair of folding doors in front of the fire chamber. The centre panels of all these doors are decorated with scroll work (h. i. j. k) as represented. The door (g fig. 3) is a counterpart of the one on the half not shown. The outer bead (p) is grooved or crimped as shewn, the inner bead (l) is similar to the bead (m) on oven door (d). The upper front plate between the doors and the corners is decorated with scrolls (n). The lower front plate is decorated (o) with an oval panel, enclosing an eagle surrounded by a rose, thistle and shamrock.

What I claim as my invention and desire to secure by Letters Patent, is the combination and arrangement of ornamental forms and figures represented in the accompanying drawings, forming an ornamental design for a Cooking Stove.
